VARIABLE WIDTH RIGID AWNING

Howard C. Riemann, West Allis, Wis., assignor to
 The Fulton Company, West Allis, Wis., a corporation of Wisconsin

Application April 17, 1948, Serial No. 21,574

11 Claims. (Cl. 160—222)

1

The present invention relates generally to improvements in overhead shelters, and relates more specifically to improvements in the construction and operation of variable width rigid awnings for windows or the like.

The primary object of my invention is to provide an improved awning assemblage for windows or the like, which may be readily varied in width so as to properly cooperate with windows of different sizes.

It has heretofore been proposed to construct window awnings of sheet-metal slats assembled to provide relatively rigid awning structures adapted to admit air and subdued light to the protected zones, while preventing ingress of direct sunrays, rain and snow to such zones; and these prior devices also embodied mechanism for adjusting some of the slats for ventilation purposes. Because of the various conditions that these prior metal awnings attempted to fulfill, they were necessarily rather complicated, costly, and cumbersome, and did not afford the rigidity and strength necessary to withstand all climates throughout the year, and the previous assemblages therefore never became highly popular with the general public.

It is therefore a more specific object of the present invention to provide an improved sheet-metal awning which is simple, compact, and durable in construction, and which may be manufactured and installed at moderate cost.

Another important object of this invention is to provide a highly effective and exceedingly rigid window awning composed of relatively few simple parts, and which may be readily applied by a novice to effectively cooperate with windows of various widths.

A further object of my invention is to provide an improved sheet-metal awning assemblage adapted for year around service in any climate, and which is highly attractive in appearance.

Still another important object of the invention is to provide an efficient permanent awning unit especially adapted for home and apartment house use, and which may be readily installed or removed.

An additional object of my present invention is to provide an improved variable width window awning structure, which may be conveniently assembled and adjusted to provide a highly effective and durable shelter.

These and other objects and advantages of the invention will be apparent from the following detailed description.

A clear conception of the improved features

2

constituting my invention and of an embodiment thereof in a typical window awning, may be had by referring to the drawings accompanying and forming a part of this specification wherein like reference characters designate the same or similar parts in the various views.

Fig. 1 is a front view of a typical variable width window awning unit incorporating the present invention;

Fig. 2 is a fragmentary bottom view of the awning assemblage of Fig. 1;

Fig. 3 is a side view of the assembled awning structure shown in Figs. 1 and 2;

Fig. 4 is a somewhat enlarged perspective view of one of the slats used in the improved awning assemblage, showing one of the frame or supporting sections attached thereto;

Fig. 5 is a further enlarged transverse section through several cooperating slats and frame sections, showing the slats adjusted for maximum awning width, and the section having been taken along the line 5—5 of Fig. 1;

Fig. 6 is a similarly enlarged fragmentary inside view of the several slats and frame sections shown in Fig. 5; and

Fig. 7 is a likewise enlarged transverse section similar to that of Fig. 5, but showing the slats adjusted for lesser awning width.

While the invention has been shown and described herein as having been embodied in a single window sheet-metal sectional awning unit especially adapted for use on homes or other dwellings, it is not my desire or intention to unnecessarily limit the utility of the improved features to such use, and it is also contemplated that specific descriptive terms employed herein be given the broadest possible interpretation consistent with the disclosure.

Referring to the drawings, the improved variable width rigid awning unit shown therein comprises in general a series of elongated longitudinally inclined rigid slats 10 disposed side by side and each having high and low parallel offset flat portions 11, 12 extending throughout its length and interconnected by a rigid transverse wall 13; and a sectional frame-work 14 for firmly but adjustably supporting the slat series with the high portion 11 of each slat 10 overlapping the low portion 12 of the adjacent slat 10. The slats 10 are preferably formed with the aid of punches and dies from non-corrosive or protectively coated sheet-metal, and are of interchangeably similar unitary construction so that any desired number of these slats 10 may be assembled in order to produce top shelters or

decks of any required width. The free edge of the high portion 11 of each of the slats 10 may be provided with a depending flange 15 and the free edge of each low portion 12 may be likewise provided with an upstanding flange 16, both formed integral with the adjacent slat portions 11, 12 as shown in Fig. 4; and since the low portions 12 of the successive slats 10 are always at the same side thereof, a special slat 17 having no low portion thereon may be provided at one end of the series in order to maintain symmetry and improved appearance in the final assemblage, as indicated in Figs. 1 and 2.

The main slats 10 may be curved at their upper ends and may also be provided at their lower extremities with vertical drip portions 18 as depicted in Fig. 3, and the lower end of each slat portion 11 may be rounded as shown in order to provide a scalloped lower edge for the assemblage. The upper and lower portions of each slat 10 are each provided with a transverse metallic frame element or section 20 permanently secured to the slat by means of a rivet 21 or by welding, and each of these frame sections 20 constitutes a part of the frame-work 14 and has a U-shaped end 22 projecting laterally beyond its carrying slat 10 as clearly illustrated in Fig. 4. The U-shaped projecting end 22 of each section 20 has an elongated slot 23 formed centrally therein; and the opposite end of each of these frame elements or sections is adapted to be telescoped within the U-shaped end 22 of the adjoining frame section 20 carried by an adjacent slat 10, and is provided with an integral internally threaded ferrule 24 formed to receive a clamping screw 25 adapted to ride along the slot 23 of the adjacent section end 22. The slots 23 and screws 25 define the limits of lateral adjustability of the adjacent overlapping slats, and when the screws 25 are driven home so as to clamp the successive frame sections 20 to each other, the awning top is supported by rigid continuous upper and lower transverse frame bars extending entirely thereacross.

The opposite sides of the awning assemblage are provided with similar but reversely disposed triangular metallic frames 26 each having inwardly directed upper and lower projections 27 formed integral therewith and adapted to be firmly secured to the adjacent frame sections 23 by means of screws 25' as indicated in Figs. 1 and 2. Each of the triangular side frames 26 may be formed of several pieces rigidly united in any suitable manner, and also constitutes a part of the main frame-work 14; and each frame 26 is provided with a top closure strip 28 extending longitudinally of and coacting with the adjacent upper slats 10, 17, and is also provided with a series of overlapping upright side slats 29 of gradually diminishing length firmly secured to the frame 26 by means of longer screws 30 as shown in Figs. 1, 2 and 3. These side closure slats 29 may also be formed with high and low portions and are permanently and fixedly attached to the adjacent side frames 26; and the slats 29 cooperate with the strips 28 to provide tight opposite side closures the lower edges of which may also be scalloped to conform with the lower scalloped edge of the front and top deck. The high and low portions of the top and side slats 10, 29 may be colored to produce attractive stripe effects, and the strips 28 as well as the slats 29, may also be formed of suitable sheet-metal with the aid of punches and dies.

When the various parts of the improved awning have been properly constructed as above

described, the opposite side frames 26, strips 28 and slats 29 may be permanently assembled and caused to coact with an intervening series of slats 10 comprising any desired number of the latter. In order to assemble the slats 10, the upstanding side flanges 16 of the successive slats should be inserted beneath the high portions 11 and within the side flanges 15 of the adjacent slats 10 whereupon the corresponding frame sections 20 should be telescoped over each other and the screws 25 should also be loosely applied to the adjacent slots 23 and ferrules 24, as illustrated in Figs. 5, 6 and 7. While the screws 25 are still loose, the several initially joined slats 10 may be shifted laterally relative to each other from the maximum expanded position shown in Fig. 5 to the minimum contracted position shown in Fig. 7, or to any desired intermediate position; and when proper adjustment has been effected, the screws 25 may be driven home so as to clamp the frame sections 20 and the sections 10 in properly adjusted position. The special end slat 17 may then be applied to the assembled top deck, and the upper and lower end sections 20 may be secured to the inwardly extending projections 27 of the triangular side frames 26 with the aid of the screws 25', thus completing the awning unit.

After an awning unit has been properly assembled and completed as above described, it may be applied to a building and firmly attached in any desired manner to provide an efficient and rigid shelter adapted to withstand even the most severe and changeable climatic conditions. The improved formation of the top slats 10, 29 with high and low integrally united portions 11, 12 and integral side flanges 15, 16 at their overlapping edges, effectively prevents water, sleet, snow, and wind from passing between the coacting slats; and the frame sections 20 secured to the upwardly inclined slats 10, not only provide for convenient adjustment of the awning width, but also cooperate with the triangular side frames 26 to produce a strong and durable composite frame work 14. The various parts of the improved awning may obviously be readily manufactured of suitable corrosion resistant sheet-metal with the aid of punches and dies with sufficient accuracy to make like parts interchangeably similar; thus making the improved units well adapted for quantity production at moderate cost and for diverse uses. The high and low portions 11, 12 of the slats 10, 29 may also be variously colored to produce attractive stripe effects, and the several parts of the improved awnings may obviously be readily assembled or dismantled with the aid of an ordinary screw driver, and may be compactly packed for shipment, storage, and final distribution to the trade. My improved awnings have proven highly satisfactory and successful in actual use, and may be manufactured in various sizes and shapes for diverse purposes at very low cost.

It should be understood that it is not desired to limit this invention to the exact details of awning construction herein specifically shown and described, for various modifications within the scope of the appended claims may occur to persons skilled in the art.

I claim:

1. In a variable width awning roof, a series of elongated slats each having a high and a low longitudinal portion interconnected by a rigid wall, said slats being disposed side by side with the high portion of one slat overlapping the low

portion or an adjoining slat, and a transverse supporting frame section secured to each slat and having an end portion overlapping the adjacent end portion of the frame section of said adjoining slat to unite the overlapped slats, said overlapped frame sections and slats being relatively adjustable laterally of the slats to vary the overall width of the united slat assembly.

2. In a variable width awning roof, a series of elongated longitudinally inclined slats having similar transverse cross-section and each having a high and a low longitudinal portion interconnected by a rigid integral wall, said slats being disposed side by side with the high portion of one slat overlapping the low portion of an adjoining slat, and a transverse supporting frame section secured to each slat and having an end portion overlapping the adjacent end portion of the supporting frame section of said adjoining slat to unite the overlapped slats, said overlapped frame sections and slats being relatively adjustable laterally of the slats to vary the overall width of the united slat assembly.

3. In a variable width awning roof, a series of elongated longitudinally inclined slats each having high and low longitudinal portions of equal width interconnected by an integral transverse wall, said slats being disposed side by side with the high portion of one slat overlapping the low portion of an adjoining slat, and a transverse elongated supporting frame section secured to the underside of each slat and having an end portion overlapping the adjacent end portion of the supporting frame section of said adjoining slat to unite the overlapped slats, said overlapped frame sections and slats being relatively adjustable laterally of the slats and longitudinally of the frame sections to vary the overall width of the united slat assembly.

4. In a variable width awning roof, a series of elongated upwardly inclined slats each having parallel off-set flat portions interconnected by a transverse wall, said slats being disposed side by side with one of said portions of one slat overlapping the other portion of an adjoining slat, a support secured to each slat and having an end portion overlapping the adjacent end portion of the support of said adjoining slat, and means for clamping said overlapped end portions of said supports to each other in various overlapped positions to vary the overall width of the united slat assembly.

5. In a variable width awning roof, a series of elongated longitudinally inclined slats each having high and low longitudinal portions of equal width interconnected by an integral transverse wall, said slats being disposed side by side with the high portion of one slat overlapping the low portion of an adjoining slat, a supporting frame section secured to the underside of each slat and having an end portion overlapping the adjacent end portion of the supporting frame section of said adjoining slat, said overlapped frame sections and slats being relatively adjustable laterally of the slats to vary the overall width of the united slat assembly, and means for clamping said overlapped end portions of said frame sections together in any position within the range of relative adjustment thereof.

6. In a variable width awning roof, a series of longitudinally inclined unitary sheet-metal slats each having a high and a low longitudinal portion interconnected by an integral transverse wall, said slats being disposed side by side with the high portion of each slat overlapping the low

portion of the adjoining slat, and a transverse elongated supporting frame for said series comprising a frame section secured to each slat and having an end portion overlapping the adjacent end portion of the frame sections of the adjoining slats, said overlapping portions of said frame sections being relatively adjustable laterally of the slats and longitudinally of said sections to vary the overall width of the slat assembly.

7. In a variable width awning roof, a series of longitudinally inclined unitary sheet-metal slats each having a high and a low longitudinal portion interconnected by an integral transverse wall, said slats being disposed side by side with the high portion of each slat overlapping the low portion of the adjoining slat, a supporting frame for said series comprising a transverse frame section secured to each slat and having opposite end portions overlapping the adjacent end portions of the frame sections of the adjoining slats, said overlapping end portions of said frame sections being relatively adjustable laterally of the slats to vary the overall width of the slat assembly, and means coacting with the overlapped end portions of said frame sections for clamping the same in any position within the range of adjustment thereof.

8. In a variable width awning roof, a series of elongated unitary sheet-metal slats each having parallel reversely disposed adjoining trough portions integrally united by a common intervening wall, one of said portions of each slat overlapping the other portion of an adjacent slat and said walls of the overlapped slats being adjustable toward and away from each other, a transverse supporting frame section secured to each slat and having an end portion overlapping the adjacent end portion of the supporting section of the adjacent slat, said overlapped ends of said supporting sections being relatively adjustable laterally of said slats, and means for clamping said frame sections in various overlapped positions.

9. In a variable width awning roof, a series of elongated rigid slats each having parallel flat off-set longitudinal portions interconnected along their adjacent edges by a transverse wall and provided along their opposite edges with reversely directed flanges, one of said flanges of each slat overlapping and engaging one flat portion of an adjoining slat and being movable transversely thereof, several transverse supporting frame sections secured to each slat and having end portions telescopically engaging the adjacent end portions of the complementary frame sections of adjoining slats, and clamping means coacting with the overlapped end portions of said frame sections.

10. In a variable width awning roof, a series of elongated rigid slats each having parallel flat off-set longitudinal portions interconnected along their adjacent edges by a transverse wall and provided along their opposite edges with reversely directed flanges, one of said flanges of each slat overlapping and engaging one flat portion of an adjoining slat and being movable transversely thereof, and several trough shaped parallel frame sections secured transversely to remote portions of each slat and having end portions telescopically engaging the adjacent end portions of the complementary frame sections of adjoining slats.

11. In a variable width awning roof, a series of elongated rigid slats each having parallel flat off-set longitudinal portions interconnected along their adjacent edges by a transverse wall and provided along their opposite edges with reversely

directed flanges, one of said flanges of each slat overlapping and engaging one flat portion of an adjoining slat and being movable transversely thereof, several trough shaped parallel frame sections secured transversely to remote portions of each slat and having end portions telescopically engaging the adjacent end portions of the complementary frame sections of adjoining slats, and means for clamping the coacting portions of said frame sections in various relative positions to vary the overall width of the slat assembly.
